CHECKERED GAME BOARD

Charles Haven Hayes, Dearborn, Mich.

Application November 23, 1945, Serial No. 630,305

1 Claim. (Cl. 273—131)

1

My invention relates to a game of skill and comprises in general a playing board on which opposing players may manipulate their play pieces in such a way as to generally advance their play pieces towards a goal and also eliminate the opposing player's pieces by forcing him to jump his piece into an elimination zone or pocket.

An object of the present invention is to construct a novel game of skill by providing a playing board on which play pieces may be moved in accordance with predetermined rules of play and including a hazard comprising an elimination zone for eliminating play pieces from play.

Various other objects of my invention will be apparent as the description progresses, same describing in detail the principles of my invention and referring to a drawing illustrating a preferred embodiment of the invention, in which,

Fig. 1 is a plan view of the playing board embodying the principles of my novel game and illustrating same in connection with men or play pieces and showing the principles of play, certain of the board squares and of the play pieces being marked to indicate colors.

Figs. 2 and 3 are detailed sectional views taken respectively on the section lines 2—2 and 3—3 of Fig. 1.

My novel game is played on a playing board 10 on which is pictured a plurality of unit play areas 11, preferably comprising a plurality of squares. While the playing board illustrated in the accompanying drawing comprises a board formed or divided into a plurality of squares numbering a total of 169, it is obvious that said unit play areas may be of other shapes and more or less in number.

A starting zone, one for each player is provided preferably in each corner, these zones having an indicated separation from the other squares on the board and being identified by reference characters 12a, 12b, 12c and 12d respectively. Play pieces 13a, 13b, 13c and 13d, preferably different in color or shape are provided and each player is provided with a plurality of such play pieces, which are initially placed on a like number of unit play areas comprising their respective starting zone. An elimination area or pocket 14 is provided preferably in the center portion of the board and may comprise a cross or other shape of some predetermined area or size. The player at starting zone 12a has as his goal the play area 15a diagonally opposite and preferably at the other extreme corner, and thus the four goals 15a, 15b, 15c and 15d lie respectively diagonally opposite the starting zones 12a,

2

12b, 12c and 12d, and the elimination area lies intermediate and substantially midway of the starting zone and the goal towards which the play pieces initially placed in the starting zone are moved. The elimination area may be merely marked on the board, or said board may be cut out as shown in the accompanying drawing. To accentuate the hazard to which men adjacent the elimination zone are subjected, certain of the squares in the vicinity of the elimination zone are colored differently from the other playing area squares and from the starting zones. As shown in Fig. 1, such squares are marked to indicate the color red, and the other squares of the playing area are unmarked to indicate white, while the squares of the several starting zones are marked to indicate the color black.

The directions or rules of play are as follows, and for convenience the play pieces are hereafter referred to as "men" and the play areas as "squares"; red, white or black as the case may be. Obviously, the various colors above referred to are selected merely as a matter of convenience and my invention is not limited to any particular or specific color, shape or arrangement, the accompanying drawing merely illustrating one preferred arrangement. For convenience I show eight black squares in each corner, each set of black squares comprising a starting zone, and each player has therefore eight men, which are placed in his eight black corner squares. The first player to move one of his men across the playing board and into the opposite goal wins the game.

1. The players move in turn, preferably clockwise of first player.

2. Each player in his turn may move his men one square in any direction except backwards.

3. Each player may jump his own or opponent's men in all directions excepting backwards, stopping at his own discretion.

4. Each player may jump across the elimination zone directly across, if his man occupies a square next to said elimination zone. At center corner squares, the player may jump his man across or diagonally, but never lengthwise as from a to b.

5. A player may eliminate an opponent's man by moving his men into such a position as to align them so that his opponent by jumping same will land into said elimination zone. The player must order said jump prior to opponent's move and must specify the move to be made, and opponent is required to jump as directed, and as many men as necessary in any direction as the case may call

for, until he ends by jumping into the elimination zone.

6. A player, on moving into the square next to an occupied goal, can order opponent's man to jump from said goal when his turn comes, providing there is an unoccupied square to jump to. No player can force a player to jump unless by so doing he will jump into said elimination zone or jump out of the goal. Only the player bearing on another player's man may order the jump.

7. In case a player is unable to move or jump, he forfeits his turn until he is able to continue.

8. If more than one opponent has a man bearing on a player ready to play, only the opponent next in turn has the right to require the player to jump.

9. A player's man must be in the square next to that occupied by an opponent in order to bear on the opponent's man.

Two, three or four players may play the game, and obviously the principles of the invention may be incorporated in other arrangements suitable for two or more players, even in excess of four players if found desirable, and the starting zones may be located in regions other than corners if so desired. The elimination zone, while preferably located in the center of the board may obviously be located at other regions, the purpose of said elimination being to set up a hazard to play and make possible the elimination of an opponent's man, but obviously same is arranged in such a way as to facilitate interest in the game and to require skillful play and planning on the part of all players.

Although I have illustrated but one form of my invention and have described in detail but a single application thereof, it will be apparent to

those skilled in the art to which my invention pertains, that various modifications and changes may be made therein without departing from the spirit of my invention or from the scope of the appended claim.

5 I claim:

10 A game board for use with two or more sets of several men each, each set of different colors, said game board having its surface divided into 10 squares and having groups of several of said squares in two or more opposite corners of said board of an indicated separation from the other squares thereon, one of said squares in each of 15 said group of squares being designated as a goal, and an elimination zone in an intermediate portion of said game board and bounded on all sides by a plurality of squares, any of said men being 20 retired from play when required to jump a man positioned in a square adjacent said elimination zone, said squares spaced from said elimination zone by a single square being differently colored to indicate danger since men positioned in such squares may be forced to jump a man in adjacent squares and thence into said elimination 25 zone.

CHARLES HAVEN HAYES.
